United States Patent Office

Des. 184,060
Patented Dec. 9, 1958

184,060

COMBINED DART AND PROJECTOR THEREFOR OR SIMILAR ARTICLE

Sidney Jay Mehr, New York, N. Y.

Application September 13, 1956, Serial No. 42,926

Term of patent 3½ years

(Cl. D34—15)

Fig. 4

Fig. 1

Fig. 2

Fig. 3

Fig. 1 is a front elevational view of a combined dart and projector therefor or similar article, showing my new design;

Fig. 2 is a side elevational view;

Fig. 3 is a rear elevational view; and

Fig. 4 is a top plan view of the projector portion.

I claim:

The ornamental design for a combined dart and projector therefor or similar article, as shown.
